CHARLES F. LYITTLE, OF SIOUX CITY, IOWA

MASONRY CREVISE-FORMING TEMPLATE

Application filed August 1, 1929. Serial No. 382,778.

This invention relates to improvements in apparatus for forming expansion joints in masonry, and more particularly road-surfacing concrete.

5 The object in view is the effective retention of the concrete cast in a position for providing a key-way or expansion crevice by apparatus possessing especially efficient means for withdrawal without injury to itself or to the concrete.

Lightness, sturdiness, and ease of repair of such apparatus are also objects of the present invention, and with these and further objects in view as will in part hereinafter be 15 come apparent and in part be stated, the invention comprises a template and means for effectively withdrawing the template after the set of the concrete without danger of injury to the concrete or to the template.

20 The invention comprises certain other novel constructions, combinations, and arrangements of parts as subsequently specified and thereafter pointed out in the appended claims.

25 In the accompanying drawings,—

Figure 1 is a top plan view of a template embodying the features of the present invention, parts being broken away for the saving of space.

30 Figure 2 is a transverse, vertical section therethrough taken on the plane indicated by line 2—2 of Figure 3.

Figure 3 is a fragmentary, vertical section taken on the plane indicated by line 3—3 of 35 Figure 2.

It has heretofore been the practice to place a wooden or metallic strip to serve as the matrix or form in which to cast concrete and in road building expansion crevices have 40 been provided by utilizing a similar plate, but after the concrete has taken its initial set, or even subsequently thereto, when withdrawal of the plate is attempted, margins of the concrete are frequently injured, and it 45 is also sometimes found extremely difficult to remove an embedded plate of this kind without the exertion of a great deal of energy and the endangering of substantial damage.

50 The present invention obviates all these difficulties by providing a crevice forming

template adapted to be withdrawn laterally instead of edgewise, and by providing means of easy manipulation for effecting such lateral withdrawal.

Referring to the drawing by numerals, 1 55 indicates a narrow, troughlike template formed preferably of a sheet of metal folded into approximately V-shape with the apex of the V rounded instead of brought to an edge. The sides of the thus-produced template are 60 each of a width equal to the depth of the masonry wall or layer of road surface, or at least of that part thereof which is to be formed with an expansion crevice. Fixed to and extending inwardly from the inner face 65 of each side plate of template 1 are buttons 2, 2, riveted or otherwise effectively anchored to the plate, and each provided with a shank 3 spacing the respective button 2 from the inner face of the respective side plate of template 1. As many buttons 2 may be employed 70 as desired, and the buttons are preferably spaced approximately equidistant in the length of the template.

With the template 1 is arranged a folded sheet, preferably of metal, forming a troughlike removable wedge 4. Wedge 4 has its side faces flush against the inner faces of the plate comprising template 1, and the said faces are formed with vertical slots 5 snugly accommodating the shanks 3 of the respective buttons 2, so that the buttons overhang the inner faces of the side plates making up wedge 4. 75 80

In operation, the template 1 is positioned to receive the cast of concrete, and the concrete is located at both sides of the template and allowed to stand until set, and thereafter the withdrawal wedge 4 is pulled upward out of the template 1. It is to be understood, of course, that usually the concrete will come flush with the upper edge of template 1, but will never overhang such edge and may fall below the edge. It is to be observed that as the withdrawal wedge 4 is pulled upward, 90 the buttons 2 having sliding engagement with the inner faces of the plates comprising the wedge 4 will be wedged laterally; that is to say, the buttons of one side plate of template 95 1 and the buttons of the other side plate will 100

be moved toward each other, so that the respective side plates of template 1 will be drawn together and thereby pulled laterally away from the cast concrete without any edge-wise movement. This wedging together of the side plates of template continues by the further upward movement of withdrawal wedge 4 until the template is entirely released from the concrete and is readily lifted above the same. It will be noted that in this action the fold at the apex or lower edge of the template 1 serves in the nature of a hinge on which the side plates of template 1 move with a springing movement, but, of course, 15 a mechanical hinge may be substituted if and when desired.

The wedge 4 is susceptible of a wide range of variation in construction, but is preferably in the form of a sheet of metal, or other appropriate material, having its upper or exposed edges cross-braced to aid in stabilizing and retaining the template 1 in operative condition during the casting and setting of the concrete. This cross-bracing may consist of 20 any acceptable stays or webbing, a simple and efficient form of cross-bracing being indicated in the drawing as produced by folded and lapped portions 6, 6, formed from the sheet of which the wedge 4 is formed. The said 25 overlapping portions 6 may be spot welded or otherwise fixed together, or, when desired, detachably connected, as by being bolted together. The cross-bracing whether of the form of folded parts 6, 6, or otherwise, is 30 provided with tool-receiving apertures 7, 7, or hand-holes to enable the operator to exert the required upward pull on the wedge 4.

After the template has been withdrawn, it can readily be conditioned for re-use by 40 merely pushing the wedge 4 back to the seated position seen best in Figure 2.

In the event of injury to any of the parts, or other occasion requiring or making desirable separation of the wedge 4 from the template 1, it is preferable to provide apertures 8, 8, having lateral passageways 9, 9, leading from the slots 5 at any appropriate point in the length of the slots, as, for example, at the upper ends thereof, so that by 45 sliding the wedge 4 longitudinally relative to the template 1 while the shanks 3 are in line with the lateral passageways 9, the buttons 2 may be located in line with the openings 8, and, as said openings are larger than 50 the buttons, the buttons may be withdrawn from the openings and the template 1 thus detached from the wedge member 4.

The wedge member 4 while referred to as a withdrawing wedge is, in fact intended to 60 and does function as a wedge in two directions. If the side plates of template 1 should become pressed together, as by being slightly crushed nearer than normally intended or otherwise distorted, the insertion of the 65 wedge 4 between said side plates will spread

the same to the normal condition; and the part 4 also functions essentially as a wedge in causing the inclined planes of its inner faces to wedge the buttons 2 toward the center and thereby pull the side plates of template 1 70 inward under a wedging action.

What is claimed is:

1. In apparatus of the class described, the combination of a substantially trough-shaped template, a wedge within the template, and means providing a sliding connection between side plates of the template and wedge for effecting inward lateral movement of the side plates incident to withdrawal movement of the wedge. 75

2. In apparatus of the class described, the combination of a substantially trough-shaped template, a wedge within the template, and means providing a sliding connection between side plates of the template and wedge for effecting inward lateral movement of the side plates incident to withdrawal movement of the wedge, the wedge comprising sheet material of trough shape. 80

3. In apparatus of the class described, the combination of a substantially trough-shaped template, a wedge within the template, and means providing a sliding connection between side plates of the template and wedge for effecting inward lateral movement of the side plates incident to withdrawal movement of the wedge, the wedge comprising sheet material of trough shape and the sliding connection comprising overlying buttons and slot engaging means. 90

4. In apparatus of the class described, the combination of a trough-shaped template, a similarly shaped wedging element within the template and having transverse slots, and buttons carried by the template and having shanks extending through said slots for enabling the buttons to overhang parts of the wedging element. 100

5. In apparatus of the class described, the combination of a template formed of a sheet material folded to trough shape, a similar sheet of material located within said template, and means at portions of the template adjacent the free margins thereof for slidably interengaging the inner sheet. 110

6. In apparatus of the class described, the combination of a template formed of a sheet of material folded to trough shape, a similar sheet of material located within said template, means at portions of the template adjacent the free margins thereof for slidably interengaging the inner sheet, and cross-bracing means for the inner sheet for resisting collapse of the template. 120

7. In apparatus of the class described, the combination of a template formed of a sheet of material folded to trough shape, a similar sheet of material located within said template, means at portions of the template adjacent the free margins thereof for sliding 125

ly interengaging the inner sheet, and cross-bracing means for the inner sheet for resisting collapse of the template, the said cross-bracing means having means for engagement of withdrawal means for withdrawing the inner sheet with respect to the template.

8. In an expansion joint apparatus of the class described, the combination of a template including laterally spaced side plates, a continuous wedge member adapted to extend substantially the full length of said template intermediate said side plates for retaining said side plates in substantial alignment, said wedge member having elongated transverse slots formed therein at intervals, and means on said template adapted to cooperate with said slots for moving the said side plates laterally toward each other incident to withdrawal movement of the wedge member.

20 9. In an apparatus of the class described, the combination of a substantially trough-shaped template formed of a continuous piece of sheet material, a correspondingly shaped wedge member formed of a continuous piece 25 of sheet material adapted to be positioned within said template, said wedge member having laterally extending flanges formed on the upper edges thereof and adapted to overlap to constitute bracing means resisting collapse of said template, and means for collapsing said template incident to withdrawal movement of said wedge member.

10. In apparatus of the class described, the combination of a template formed of a sheet 35 of material folded to trough-shape, a similar sheet of material located within said template, and means at portions of said template adjacent to the free margins thereof for slidably interengaging the inner sheet, said inner sheet having means whereby the said template and inner sheet may be disengaged incident to a preliminary relative longitudinal movement of said template and inner sheet.

40 11. In apparatus of the class described, the combination of a trough-shaped template, a similar shaped wedging element within the template and having transverse slots, and buttons carried by the template having shanks extending through said slots for enabling the 45 buttons to overhang parts of the wedging element, said wedging element having openings associated with said transverse slots whereby the said template and inner sheet 50 may be disengaged.

55 In testimony whereof I affix my signature.
CHARLES F. LYTLE.
